CLAIM

The ornamental design for extensions for headwear visor, as shown and described.

DESCRIPTION

FIG. 1 is a front-top-left perspective view of extensions for headwear visor showing my new design;

FIG. 2 is a rear-bottom-left perspective view thereof;

FIG. 3 is a rear-top-right perspective view thereof;

FIG. 4 is a front elevational view thereof;

FIG. 5 is a rear elevational view thereof;

FIG. 6 is a top plan view thereof;

FIG. 7 is a bottom view thereof;

FIG. 8 is a right-side elevational view thereof; and,

FIG. 9 is a left-side elevational view thereof.

The broken lines showing of headwear in FIGS. 1-9 are included for the purpose of showing environmental structure and form no part of the claimed design.

1 Claim, 9 Drawing Sheets
